UNITED STATES PATENT OFFICE.

JACOB A. MATTERN, OF DES MOINES, IOWA.

FIRE-ESCAPE.

1,300,752.

Specification of Letters Patent.

Patented Apr. 15, 1919.

Application filed July 16, 1918. Serial No. 245,179.

To all whom it may concern:

Be it known that I, JACOB A. MATTERN, a citizen of the United States, and a resident of Des Moines, in the county of Polk and 5 State of Iowa, have invented a certain new and useful Fire-Escape, of which the following is a specification.

The object of my invention is to provide a simple and inexpensive fire escape which can 10 readily be moved from one room to another, or from one building to another.

More particularly it is my object to provide a fire escape comprising a rope or flexible device having fastening devices at its opposite ends, and having mounted thereon a 15 slideable clamp, with means for automatically holding the clamp locked on the rope, said clamp having a handle or the like whereby its grip on the rope may be released, so that 20 the weight of a person supported on the clamp will cause it to slide down the rope at any desired speed.

Still a further object is to provide such a device so constructed and arranged that the 25 rope may be fastened by either end and the clamp device may be used for sliding in either direction with relation to the rope.

With these and other objects in view my invention consists in the construction, arrangement and combination of the various 30 parts of the device, whereby the objects contemplated are attained, as hereinafter more fully set forth, pointed out in my claims and illustrated in the accompanying drawings, in which:

Figure 1 shows my improved fire escape having one end extending to the interior of the building through a window therein.

Fig. 2 shows a side elevation of a clamp 40 installed on a rope.

Fig. 3 shows a front elevation of the same.

Fig. 4 shows a top or plan view of the clamp, the rope being shown in section.

Fig. 5 shows a face view of one of the 45 cams; and.

Fig. 6 shows a side elevation of the same.

In the accompanying drawings, I have used the reference numeral 10 to indicate generally a rope or suitable flexible device having 50 at its ends rings 11 designed to be adjacent to a hook inside the building, so that the rope may be extended through the window to the outside of the building.

Mounted on the rope 10 is a clamp device 55 comprising a pair of opposite coacting clamp

members 12 and 13 hinged along one longitudinal edge 14.

At the other edges of the clamp members 12 are laterally extending flanges 15 and 16. The parts are so arranged that when the rope 60 10 is firmly gripped between the clamp members 12 and 13, the flanges 15 and 16 will be slightly spaced from each other.

Extended through the flanges 15 and 16 is a pair of spaced bolts 17 having on their ends 65 nuts 18.

On each bolt 17, adjacent to the flange 16, is a cam-faced washer 19 having one flat sided edge 20 adjacent to the clamp member 13, which, by its engagement with the 70 clamp member 13, prevents rotation of the washer 19.

Mounted on the upper bolt 17 is a lever or handle 21 having formed thereon adjacent to the washer 19 a cam face 22.

Mounted on the other bolt 22 is an arm 23 having a similar cam face. The arm 23 and lever 21 are pivoted to the ends of a link 24.

Secured to the clamp member 13 is a coil 80 spring 25, which, at its other end, is secured to the lever 21 and is designed to hold the lever 21 and arm 23 in such positions as to clamp the clamp members 12 and 13 firmly on the rope 10.

In Figs. 2 and 3 I have shown the lever 21 and the cams in their position assumed when the person using the fire escape moves the lever to position for releasing the grip of the clamp members on the rope.

As soon as the person releases his hold on the lever, the spring 25 moves the parts to position for tightening the grip of the clamp on the rope.

Secured to the clamp member 12 is a loop 95 26 on which is loosely mounted a ring 27, through which is extended a strap or the like 28. This loop 26 is also shaped and designed to form a handle which may be grasped by the operator in one hand and used to steady 100 the machine, and to assist the operator in relieving the weight on the strap.

In the practical use of my improved fire escape, the user throws the loose end of the rope out through the window after one end 105 of the rope has been securely fastened over a hook or the like. The strap 28 may then be placed around the body and the user climbs out of the window. The spring will hold the rope so tightly gripped as to prevent the de- 110

scent of the user of the fire escape until the user grasps the lever 21 and moves it to its position shown in Figs. 2 and 3, for moving the cam faces of the lever 21 and arm 23 to such positions with relation to the cam-faced washers 19 as to permit the spreading of the clamp members 13, so that the clamp members can slide on the rope 10.

10 The speed of the descent may be easily controlled by manipulation of the lever 21.

On account of the arrangement of the spring 25 it is obvious that if the user of the device should become frightened and release his grip on the lever, the spring will automatically cause the clamp members to grip the rope for stopping the descent of the user.

Furthermore the device is intended to be preferably used in the position shown in the figures in the drawings, so that if the user 20 should become frightened his natural tendency would be to draw downwardly on the handle of the lever, which would simply assist the spring in causing the clamp members to grip the rope.

25 However, my device is so made that in emergency if one person should use the fire escape, then the next person may simply pull in the rope and fasten the other end inside the building, and may descend with the 30 clamp device simply reversed end for end from the position shown in the drawings.

It will be seen that on account of the use of the yoke 26, the ring 27 and shoulder 28 may be slid so as to be used conveniently in 35 either of the positions of the clamp devices.

My improved fire escape is of very simple and inexpensive construction; is positive in its operation; is automatically rendered safe against too rapid descent by the user; and 40 may be readily used when the clamp device is on either end of the rope, so that it is not necessary to slide the device over the rope from one end to the other after the rope has been used once before it can be used again.

45 Some changes may be made in the con-

struction and arrangement of the parts of improved device without departing from the essential features and purposes of my invention, and it is my intention to cover by my application any modified forms of structure or use of mechanical equivalents, which may be reasonably included within the scope of my claims.

I claim as my invention:

1. In a device of the class described, a rope 55 having fastening devices at its ends, a pair of clamp members hinged together along one edge and designed to grip said rope, said clamp members having at their opposite edges spaced flanges, bolts extended through said flanges, cam-faced members on said bolts; a lever on one of said bolts having a coacting cam face, an arm on the other of said bolts having a coacting cam face, a link pivoted to said arm and said lever for causing them to act in unison, a spring secured to one of said clamp members and to said lever for normally holding the parts in position with the rope gripped between the clamp members.

2. In a device of the class described, a rope 70 having fastening devices at its ends, a pair of clamp members hinged together along one edge and designed to grip said rope, said clamp members having at their opposite edges spaced flanges, bolts extended through 75 said flanges, cam-faced members on said bolts, a lever on one of said bolts having a coacting cam face, an arm on the other of said bolts having a coacting cam face, a link pivoted to said arm and said lever for caus- 80 ing them to act in unison, a spring secured to one of said clamp members and to said lever for normally holding the parts in position with the rope gripped between the clamp members, a loop on one of said clamp mem- 85 bers, a ring loosely mounted on said loop, and a holding member extended through said ring.

Des Moines, Iowa, July 6, 1918.

JACOB A. MATTERN.
